(57) **CLAIM**

The ornamental design for a cover and decorative frame for electric switch, as shown and described.

DESCRIPTION

FIG. 1. is a perspective view representative of a cover and decorative frame for electric switch, illustrating my new design.

FIG. 2 is a front elevation view of the set described in FIG. 1.

FIG. 3 is a right-side elevation view of the set described in FIG. 1; and,

FIG. 4 is top view of the set described in FIG. 1.

The broken line showing of environment is for illustrative purposes only and forms no part of the claimed design.
